[57] CLAIM

The ornamental design for a multi-purpose hand tool, as shown and described.

DESCRIPTION

FIG. 1 is a top, front and left side perspective view of a multi-purpose hand tool showing my new design shown in an alternate condition of use;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken line showing of a writing instrument and push-pen are for illustrative purposes only and forms no part of the claimed design.
